UNITED STATES PATENT OFFICE

111,217

DESIGN FOR A FOOD CHOPPER

Hans E. A. Rable, Philadelphia, Pa., assignor to
The Enterprise Manufacturing Company of Pennsylvania, Philadelphia, Pa., a corporation of Pennsylvania

Application June 13, 1938, Serial No. 77,812

Term of patent 7 years

To all whom it may concern:

Be it known that I, Hans E. A. Rable, a citizen of the Republic of Austria (having declared my intention of becoming a citizen of the United States) residing in Philadelphia, Philadelphia County, Pennsylvania, have invented a new, original, and ornamental design for a Food Chopper, of which the following is a specification, reference being had to the accompanying drawing, forming a part thereof, in which the figure is a perspective view of a food chopper showing my new design.

The side opposite to the side shown is substantially the same in appearance.

I claim:

The ornamental design for a food chopper, substantially as shown and described.

HANS E. A. RABLE.
